UNITED STATES PATENT OFFICE.

GUST A. PETERSON, OF ROCKFORD, ILLINOIS, ASSIGNOR TO SCHÜMANN PIANO COMPANY, OF ROCKFORD, ILLINOIS, A CORPORATION OF ILLINOIS.

TRACKING, TRANSPOSING, AND SUSTAINING DEVICE.

1,275,300.

Specification of Letters Patent. Patented Aug. 13, 1918.

Application filed November 29, 1915. Serial No. 64,026.

To all whom it may concern:

Be it known that I, GUST A. PETERSON, a citizen of the United States, residing at Rockford, in the county of Winnebago and State of Illinois, have invented certain new and useful Improvements in Tracking, Transposing, and Sustaining Devices, of which the following is a specification.

This invention relates in general to apparatus employing a perforated sheet adapted to travel over a tracker bar having ducts with which the said perforations register to control pneumatic devices, and has more particular reference to apparatus of this character embodied in mechanical musical instruments, such, for instance, as player pianos.

It is well known that in the use of player pianos imperfect registration of the note sheet perforations with the ducts of the tracker bar is inimical to perfect production of music; and to insure against this occurrence various means known as automatic trackers have been devised for maintaining correct registration of the note sheet with the tracker bar by moving either with respect to the other in a direction transverse to the line of travel of the sheet, when the sheet runs out of alinement with the tracker bar. Furthermore in order to play in different keys, transposing devices whereby the tracker bar may be shifted at will transversely to the line of travel of the note sheet to register a new series of note ducts with the perforations of the sheet have been employed. Thus, by shifting the tracker bar either to the right or left the distance of one or more note ducts, the piece may be played in different keys, higher or lower, according to the adjustment.

While both transposing and automatic tracking devices have been used separately on player pianos, so far as I am aware, they have never been combined in one mechanism so that transposing can be effected at will and at the same time the sheet be controlled by an automatic tracker. The primary object of my invention is to provide such a device, that is, one in which registration of the perforations of the note sheet with the ducts of the tracker bar will be automatically maintained and in which transposing to higher or lower keys may be effected at will without disturbing the functions of the automatic tracker.

Another object of my invention is to provide a device of this character which will be simple in construction and operation and thoroughly practical commercially.

My invention also contemplates the provision of a combined transposing and automatic tracking device by which a transposition to the extent of six keys may be made; and the provision of a sustaining or damper-control device, the function of which will not be affected either by transposing to different keys or by the operation of the automatic tracker.

In carrying my invention into effect, I have developed and produced several embodiments, each of which contains certain characteristics common to all but differing in minor details, as will appear hereinafter. My invention is characterized, generally speaking, by the provision of a tracker bar having relatively movable portions, one containing a series of note ducts with which the perforations of a note sheet are adapted to register and the other a duct with which a marginal portion of the note sheet co-operates for controlling a pneumatically operated device which actuates the tracker bar to effect automatic tracking. The tracker bar is so constructed that when the sheet perforations run out of alinement with the tracker ducts, a pneumatic device will be operated to restore alinement by shifting the bar, both note and tracker portions in unison, either to the right or left, and is furthermore so constructed that the note duct portion of the tracker bar may be shifted either to the right or left relatively to the note sheet and independently of the tracker duct portion to effect transposing without disturbing the automatic tracking functions of the device, because the tracking portions of the bar remain substantially stationary and in co-operative relation with an edge of the note sheet. To obtain sustaining or damper control under all conditions of operations, I have provided the tracking duct portion of the tracker bar with a duct leading to the damper-control so that the line of sustaining perforations, which are disposed at a fixed distance from one edge of the sheet, will always register with the sustaining duct on the tracker bar; since this duct is in fixed relation with the tracking duct, which, as described above, remains stationary when the note duct portion of the bar is

shifted in the act of transposing. The construction of the tracker bar and its co-operating devices and the operation thereof will be fully understood by reference to the following description when considered in connection with the accompanying drawings, wherein—

Figure 1 is a front elevation of a spool box, upon which is mounted a tracking, transposing and sustaining device embodying the principles of my invention, the device being shown in normal position;

Fig. 2 is a plan sectional view taken on the line 2—2 of Fig. 1;

Fig. 3 is a fragmentary vertical sectional view taken on the line 3—3 of Fig. 1;

Fig. 4 is a detail view in perspective of the tracking and sustaining duct portion of the tracker bar shown in Fig. 1;

Figs. 5 and 6 are fragmentary views of the tracker bar shown in Fig. 1 transposed to extreme low and high keys, respectively;

Fig. 7 is a front elevation of a modified form of my invention;

Fig. 8 is a plan sectional view taken on the line 8—8 of Fig. 7;

Fig. 9 is a front elevation of another modified form of my invention;

Fig. 10 is a plan sectional view taken on the line 10—10 of Fig. 9; and

Fig. 11 is an enlarged vertical sectional view taken longitudinally through the tracker bar shown in Fig. 9.

Referring to the drawings, it will be noted that my improvements are mounted on a conventional form of spool box comprising a base 12 and uprights 13 and 14 interposed between and upon which are mounted in vertically spaced relation a music roll 15 and a take-up or winding-on roll 16. These rolls are fixed against axial displacement so that a note sheet 17 carried thereby will be run in a substantially fixed path over a tracker bar designated in general by reference character 18 interposed between the rolls and slidably mounted on the uprights 13 and 14 so as to be movable transversely to the line of travel of the note sheet.

Referring now to the embodiment of my invention shown in Figs. 1 to 6 inclusive, it will be noted that the tracker bar comprises a major or note duct portion 19 and end or tracking duct portions 21 and 22, designated generally by the respective reference characters. The ends of the tracker bar portion 19 are slidably mounted in recesses 23 in the face of the uprights 13 and 14 and held against outward displacement by plates 24 suitably secured to the uprights 13 and 14 in front of the tracker bar. The major portion of the tracker bar is slotted centrally and lengthwise at each end as at 25 to slidably receive the end portions 21 and 22, which are provided with splines 26 fitting in grooves in the major portion so as to be

guided in movement lengthwise of the tracker bar. The major portion of the tracker bar is provided intermediate its slotted ends with the usual note ducts 27 with which the perforations of the note sheet are adapted to register. The end portions 21 and 22, the faces of which are flush with the faces of the major portion 19, are provided with tracking ducts 28 and 29 respectively, and the portion 21 is provided with an additional duct 31, termed a sustaining duct. It should be understood that these ducts lead to and control the operation of their respective pneumatically operated devices, that is, the note ducts 27 lead to the action pneumatics, the sustaining duct 31 to the damper-control, and the tracking ducts 28 and 29 to a pneumatic device adapted to effect shifting of the tracker bar and which will be more particularly described hereinafter.

The end portions 21 and 22 of the tracker bar are connected together by means of a tie rod 32 secured at its ends by screws 33 to the said end portions so that the same will be maintained at all times in fixed relative relation. A connection is established between the end portions 21 and 22 and the major portion 19 of the tracker bar, which permits either the tracker bar as an entirety to be moved transversely to the line of travel of the note sheet or the portion 19 to be moved in said transverse direction independently of and with respect to the end portions 21 and 22. In this instance, this connection is in the form of a screw shaft 34 journaled at one end in a rearward extension 35 of the tracking duct portion 21 and threaded at its opposite end in a nut member 36 fixed to the adjacent end of the note duct portion 19, the screw shaft being held against axial displacement with respect to the tracking duct portion 21 by means of a spur gear 37 fixed to the screw shaft at the outer side of the journal 35 and a pin 38 passing through the shaft at the inner side of said journal. Thus, through the agency of the tie rod 32 and screw shaft 34 the note and tracking duct portions of the tracker bar are connected so as to be movable as a unit transversely to the line of travel of the note sheet, and upon turning the shaft 34 the note duct portion and tracking duct portions may be moved relatively in said transverse direction. This relative movement of the note and tracking duct portions is facilitated by the provisions of an adjusting wheel 39 disposed at the inner side of the upright 13 and fixedly mounted on a shaft 41 passing through the said upright and having secured to its outer end a spur gear 42 meshing with the spur gear 37. From the foregoing it will be apparent that the screw shaft 34 may be turned by an operator turning the wheel 39.

Shifting the tracker bar as an entirety transversely to the direction of travel of the note sheet is effected by a pneumatically operated device in the following manner: A lever 43 pivoted intermediate its ends at 44 to a plate 45 fixedly secured to the upright 13 is pivotally connected at 46 to the tracking duct portion 21 and pivotally connected at its opposite end through the medium of a link 47 to a double acting pneumatic 48. This pneumatic is designed to rock the lever 43 on its fixed pivot 44 in either direction so as to shift the tracker bar either to the left or right, it being apparent that during such movement of the tracker bar the spur gear 37 will be moved likewise, although the movement is so slight that it does not unmesh the gears. A connection, (not shown) is established between each tracking duct 28 and 29 and a conduit 49 leading to one of the bellows of the double pneumatic 48. A constant predetermined vacuum or suction is maintained in the pneumatic by suitable means, as is well understood in this art, so that when the tracking ducts 28 and 29 are covered the pneumatic will remain inactive, while if either tracking duct is uncovered sufficiently to admit air to its respective bellows, this bellows will be expanded so as to rock the lever 43 and move the tracker bar. Thus, when the note sheet 17 is running normally with its note perforations properly registering or tracking with the note ducts 27 on the tracker bar, the edges or marginal portions of the note sheet will just cover the tracking ducts 28 and 29, as shown in Fig. 1. As sometimes occurs, either because the note sheet shifts slightly to the right or left with respect to the tracker bar or for other reasons, the perforations of the note sheet run out of alignment with the note ducts of the tracker bar thereby impairing the quality of the music. This lateral displacement of the note sheet uncovers one of the tracking apertures, admitting air thereto and causing the pneumatic device to shift the bar in a direction to restore the note ducts of the tracker bar to proper registration with the perforations of the note sheet. From the foregoing, it will be apparent that the several portions of the tracker bar are automatically moved as a unit either to the right or left to restore registration of the perforations of the note sheet with the ducts of the tracker bar. In this connection it should be understood that I have combined an automatic tracking device in a novel manner with other features, the functions of which will be described hereinafter and that my invention does not reside in the particular form or type of automatic tracking device illustrated, but other forms of such devices well known in this art may be employed.

Coming now to the feature of transposing

from one key to another, it will be noted, viewing Fig. 1, that the tracking duct portion 22 is provided with six graduations representing different keys in which the music may be played, the line 51 representing 70 middle C. The tracker bar portion 19 contains an arrow co-operating with this key scale and, as shown in Fig. 1, the several portions of the tracker bar are so positioned that the arrow is opposite to the graduation 75 representing middle C. This is the scale in which music sheets are designed to be normally played, but by moving the note duct portion of the tracker bar to the right or left relatively to the tracking duct portions 80 21 and 22 the distance of one or more notches a new series of tracker ducts will be brought into registration with the note perforations so as to play in a different key. It will be seen that the tracker bar may be 85 moved three notches to the left, which produces playing in lower keys and two notches to the right for higher keys, the range being six keys. Since the tracker bar as an entirety is normally held stationary by reason of the fixed anchorage at the point 44 and the inactivity of the pneumatic 48 due to proper co-operation of the note sheet with the tracking duct portions 21 and 22, it will be observed that the note duct portion 19 90 may be moved either to the right or left with respect to said tracking duct portions without disturbing either their co-operation with the note sheet or the pneumatic device. Thus, by turning the hand wheel 39 the 100 screw 34 will be turned to feed the note duct portion 19 either to the right or left relatively to the tracking duct portions 21 and 22 to transpose either to a higher or lower key. When making such an adjustment, the 105 note duct portion 19 is moved until its arrow is opposite the desired key graduation on the portion 22. It will be apparent that while such adjustment is being made the tracking duct portions 21 and 22 remained substantially stationary and that after the transposition has been made by setting the arrow indicator opposite the desired key graduation if the note perforations do not properly track, the pneumatic device will be 110 automatically actuated to restore proper tracking.

In Fig. 5, I have shown the tracker bar transposed to the extreme left hand position for playing in the lowest key and in Fig. 6 the 120 tracker bar in the extreme right hand position for playing in the highest key. In these figures as in Fig. 1, it will be noted that the end portions 21 and 22 remain in the same relation to the note sheet so that the sustaining duct 31 is maintained in alignment with the sustaining perforations as long as the note sheet tracks properly with the tracking ducts.

In Figs. 7 and 8, I have shown another 130

embodiment of my invention in which it will be noted that the major portion 52 of the tracking bar contains tracking ducts 28' and 29' and a sustaining duct 31', and that it is mounted to slide to the right and left on the uprights 13 and 14 similarly to the major portion 19 of the first described tracker bar. The major portion 52 of the tracker bar is slotted centrally as at 53 and formed with 10 grooves 54 to slidably receive guide ribs of a note duct portion 55. A screw 56 mounted on the tracking duct portion 52 so as to be incapable of axial displacement with respect thereto and threaded into a nut 57 secured 15 to the note duct portion 55 is adapted to be rotated by a gear-operated device similar to that shown in the first embodiment for adjusting the note duct portion transversely to the line of travel of the note sheet and 20 relatively to the tracking duct portion 52. A pneumatically operated device similar to the first described, including a lever 43' is provided for shifting the tracker bar to the right or left for effecting automatic tracking, it being noted that the forward end of 25 the lever is connected to the tracking duct portion 52 by means of a link 58. In this, as in the first embodiment, the tracking duct portion contains a graduated scale representing the different keys in which the music 30 may be played, and in the present instance, it will be observed that the pointer or indicator 59 is connected to the note duct portion 55 at the rear side thereof.

35 A brief explanation will suffice for an understanding of the operation of this form of invention. Upon turning the hand wheel 39' the note duct portion 55 may be shifted to transpose to higher or lower keys and, 40 after having been set at a predetermined key represented by the indicator 59, the tracking mechanism will be effective for maintaining the note sheet and tracker bar in proper relation.

45 Referring now to Figs. 9, 10 and 11 in which I have shown still another embodiment of my invention, it will be observed that the tracker bar comprises a major portion 61 containing note ducts and end or tracking duct portions 62 and 63 slidably mounted 50 in the uprights 13 and 14 and slidably connected with the major portion 61 so that the latter may be moved transversely to the line of travel of the note sheet and relatively 55 to the said end portions 62. The said end portions 62 and 63 have reduced inner ends 64 slidably fitting in slots in the major portion 61, the said portions 64 containing tracking apertures 28'' and 29'' and a sus- 60 taining aperture 31''. Means for guiding and maintaining the tracker portions in operative relation to the major portion 61 are provided in the form of two pairs of rods 65 and 66 secured in the ends of the 65 said portion 61, upon which rods the track-

ing duct portions 62 and 63 are respectively slidably mounted. The tracking duct portions are held in fixed relation by means of a tie rod 32'' similar to that shown in the first described embodiment and the tracker 70 bar is adapted to be shifted for tracking by a pneumatically operated device similar to that shown in the first described embodiment including a double action pneumatic 48'', a lever 43'' and link 58'. Referring to Fig. 75 11, it will be observed that the upper rod 66 is threaded at its outer end to receive a nut 67 confined in the tracking duct portion 63 against axial displacement. Upon turning the nut 67, the note duct portion will be 80 moved either to the left or right relatively to the tracking duct portions, since these are maintained stationary by reason of their connection with the automatic tracking mechanism. It will be readily apparent that 85 adjustment by means of the nut 67 effects transposing to different keys. As in the second described embodiment, the tracking portion at the right hand of the tracking bar is provided with a graduated key scale 90 with which coöperates an indicator 59' secured to the note duct portion. The operation of the last described embodiment is similar in every respect to those previously described, the difference being merely in the 95 particular form of the tracker bar portions and the method of adjusting the same relatively to effect transposing.

Referring to the several embodiments, it will be observed that in each the note sheet 100 contacts with the tracker bar throughout the length of the sheet, since at no point in the tracker bar are there gaps extending entirely crosswise thereof in which the note sheet might sag so as to displace its perforations 105 from proper registration with ducts on the tracker bar. It should also be understood that any suitable means may be provided for indicating in what key the tracking duct portion is set for playing.

While in the foregoing, I have illustrated my invention by means of several embodiments, each of which, however, contain certain characteristics common to all, it should be understood that my objects may be carried into practice by various forms of transposing and automatic tracking devices so combined as to effect the principles of my invention. Hence, it should be understood that my improvements are not to be circumscribed by changes in construction and design which are still within the spirit and scope of the invention as set forth in the appended claims.

I claim:

1. In an automatic musical instrument, the combination of a spool supporting frame, a tracker bar slidable transversely of said frame, said tracker bar comprising a pair of rigidly connected end portions pro- 130

vided with tracking-controlling apertures and an intermediate portion provided with note controlling apertures, means for adjusting said intermediate portion longitudinally with respect to said end portions for note transposition purposes, and means for automatically shifting said tracker bar bodily transversely of the frame to maintain registration between a note sheet and said 10 tracker bar.

2. In an automatic musical instrument, the combination of a frame, a tracker bar 15 slideable transversely of said frame, said tracker bar comprising rigidly connected end portions provided with tracking-controlling apertures and an intermediate portion disposed between said end portions and provided with note-controlling apertures, the note-controlling and tracking-controlling apertures of said tracker bar being all 20 disposed in substantial alinement transversely of the frame, means for adjusting said intermediate portion relatively to said end portions transversely of the frame for note transposition purposes, and means for automatically adjusting said end portions 25

and intermediate portion together as a unit transversely of said frame to maintain tracking relation between said tracker bar and an overlying note sheet. 30

3. In an automatic musical instrument, the combination of a frame, a tracker bar slideable on said frame and comprising an intermediate portion provided with note-controlling apertures and rigidly connected 35 end portions provided with tracking-controlling apertures, said intermediate and end portions being disposed in longitudinal alinement and slidably connected so as to permit longitudinal adjustment of the intermediate portion with respect to the end portions but to prevent transverse relative movement between said portions, means for manually adjusting said intermediate portion longitudinally with respect to said end 40 portions, and means for automatically adjusting the tracker bar comprising said portions bodily, transversely of the frame to maintain tracking alinement between said tracker bar and an overlying note sheet. 45

GUST A. PETERSON.
